H. DE WALLACE

BOTTLE CLOSURE

Filed March 18, 1927

Harry Dr Wallace.

UNITED STATES PATENT OFFICE.

HARRY DE WALLACE, OF SYRACUSE, NEW YORK, ASSIGNOR TO KLEEN KAP CORPORATION, OF SYRACUSE, NEW YORK, A CORPORATION OF NEW YORK.

BOTTLE CLOSURE.

Application filed March 18, 1927. Serial No. 176,522.

- This invention relates to new and useful improvements in sanitary bottle closures, designed for milk and other bottles, and has for its object to provide a one-piece fibrous closure formed with a convex apron that overlies the bead that surrounds the bottle mouth, and having a substantially flat disc-shaped central portion that seats upon the annular bottom of the recess of the mouth, the said disc being formed with a convex annular reinforcing rib that stiffens its relatively thin body. A further object is to provide concentric annular creases in the opposite faces of the closure for facilitating the depression of the central portion into the recess, one of said creases being formed in the top face of the closure adjacent the periphery of the central portion for effecting an angular fold of the closure to conform to the bottom of the recess; the other annular crease being formed in the bottom face of the closure within the convex apron for enabling the said apron to readily and snugly conform to and fit the bead of the mouth, the said closure beyond the smaller annular crease being formed with radial creases that enable the closure to contract without wrinkling when the closure is forcibly applied to the bottle mouth. And a further object is to provide a bottle closure of the character, that may be packed in magazines or other containers in close order and from which the closures may be fed singly towards the capping machines without interference from the adjacent closures.
- The various features and parts of the invention will be understood from the detailed description which follows, and by reference to the accompanying drawing, in which—
- Figure 1 is an edge view of the fibrous disc from which the closure is formed. Fig. 2 is a central vertical section, taken on line 2—2 of Fig. 5. Fig. 3 is a central vertical section showing the closure applied to a bottle ready to be forced into its mouth, by the capping plunger. Fig. 4 is a similar view, showing the closure seated in the recess of the mouth. Fig. 5 is a top plan view of the closure shown in Figs. 2 and 3. Fig. 6 is a top plan view of the closure shown in Fig. 4. Fig. 7 is a plan view of the closure, as in Figs. 2 and 3, showing its top surface formed with radial creases. And Fig. 8 is a broken elevation of a magazine from which the closures are fed into the capping machine, showing the close stacking of the closures. All of the views are enlarged for clearness.
- In the drawing, 2 represents the neck of an ordinary milk or cream bottle, 3 is the mouth, the latter being surrounded by a flaring bead 3'. 4 represents the recess of the mouth, and 5 is the usual annular ledge or seat, which supports the closure.
- 6 represents the closure, which consists primarily of a circular plane body of flexible fiber, generally known as pulp-board (see Fig. 1). In manufacturing the closure, the body 2 is operated upon by dies, which may simultaneously, or by separate operations form or roll the convex marginal apron 6'. This leaves a central disc-shaped portion 6^a, which is larger in diameter than the bottom of the recess 4 (see Figs. 2 and 3). At the base or inner circumference of the primary apron of Figs. 2 and 3, the underside of the body is formed with an annular crease 6^b, and within and concentric to said crease a similar crease, as 6^c, is formed in the top face of the body 6. The latter crease has a diameter substantially equal to the diameter of the recess 4 at the plane of the ledge 5. The creases 6^b—6^c are preferably V-shaped and are so arranged that the fiber at either side of said creases may be bent or folded substantially at right angles, as shown at α , in Fig. 4. Within and concentric to the crease 6^c the central portion 6^a is preferably formed with a convex annular rib 6^d. This rib is provided for stiffening the relatively thin medial portion of the closure and the height of said rib is preferably equal to the elevation of the primary apron 6', shown in Figs. 2, 3 and 8. This latter provision enables a number of the closures to be stacked in magazines, or other containers, and to be ejected from the magazines singly without interference from the adjacent closures. This feature will be understood by reference to Fig. 8. In this view, the magazine 7 is provided with an opening 7' in its bottom through which the lowermost closure may be ejected in a well-known manner, by means of a shuttle-like ram or plunger, as 7^a. It will be also understood from Fig. 8 that the annular ribs 6^d tend to support the medial portions 6^a of the closures, and prevent the said portions from sinking into

the shallow depressions indicated at 6^e, in Figs. 2 and 7 and effecting the interlocking of the adjacent closures. By primarily molding the closures, as shown in Figs. 2, 5 3 and 7, the closures have a normal depth of less than one-eighth inch, which is very desirable, especially for storage, shipment and magazine feeding.

In order to facilitate the depressing of the 10 medial portion 6^a of the closure for effecting the close seating or contact of the closure with the recess of the bottle mouth, the primary discs 6 are preferably formed with a relatively large number of radial creases, as 15 6^x, as best seen in Fig. 7. The creases 6^x are necessary in order that the relatively large area lying between the rib 6^a and the primary apron 6' may be suitably contracted and crowded into the recess 4, without causing 20 wrinkles or other imperfections, as shown in Fig. 4, by the ordinary pressure exerted by the capping plunger, as 8. The creases 6^x are preferably broader and deeper where they intersect with the crease 6^e, at which 25 point the contraction of the closure is greatest, in order to enable the fiber to be crowded into the narrowest part of the recess 4. The plane portion within the rib 6^a may be uti-

lized for printing the dairymen's names, or other information.

Having thus described my invention, what I claim, is—

In a bottle closure, a body having a plane disk-like central portion and an upwardly extending convex reinforcing rib defining 35 the marginal edge of said central portion, said body having an upwardly facing annular V-shaped groove concentric with and spaced from said rib, said body having a second V-shaped groove formed in its under 40 face and concentric with the first named groove, and the portion of the body extending beyond the last named groove being formed to provide a relatively broad convex apron having inwardly extending radially 45 disposed grooves overlying the second named groove and connecting with and terminating at the first named annular groove, all of said grooves forming weakened portions whereby the central portion of the body may be forced 50 into the bottle mouth and the apron portion of the body conformed to overlie the bead of the bottle.

In testimony whereof I affix my signature.

HARRY DE WALLACE.
